(57) **CLAIM**

The ornamental design for a flashlight as shown and described.

DESCRIPTION

FIG. 1 is a front, top perspective view of a flashlight showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, bottom perspective view thereof;

FIG. 9 is an enlarged detail view taken from portion 9 of FIG. 2; and,

FIG. 10 is an enlarged detail view taken from portion 10 of FIG. 3.

In FIGS. 2, 3, 9 and 10, the broken lines represent enlarged sectional designations that form no part of the claim.

The broken lines depict portions of the flashlight that form no part of the claimed design.

1 Claim, 10 Drawing Sheets
